ADJUSTABLE RAIL BRACE

Application filed February 24, 1930. Serial No. 430,518.

This invention relates in general to rail supports and particularly to rail braces cooperating with base plates.

The primary object of the invention is to provide an improved base plate and rail brace to support a rail rigidly against sidewise movement, particularly at and adjacent to switch points.

Another object is to provide a rail brace having new and novel means for fastening the brace to the plate and tie.

Another object is to provide a wedge of improved construction to cooperate with the rail brace and plate.

15 A further object is to provide a plate for supporting a rail and a rail brace having means cooperating with the plate, a wedge cooperating with the rail brace and plate for rigidly bracing the rail and for taking up 20 wear between the rail, plate and brace.

Numerous other objects and advantages will be apparent throughout the progress of the following specification.

The invention comprises in general a plate 25 which is supported on the usual tie and which supports a rail. The plate is provided with a shoulder for engaging one of the rail side flanges, and at a point remotely situated from the rail there is provided an upstanding

30 member which engages one side of a wedge. A rail brace is provided with a horizontal surface adapted to rest upon the upper face of the plate and has a vertical surface adapted to bear against the web of the rail. An 35 inclined portion integrally connects the horizontal and vertical portions of the brace and is made to conform with the shape of the rail flange. One side of the brace is provided with a portion inclining at an angle to the

40 longitudinal center line of the rail to receive the wedge. The wedge is provided with a plurality of rectangular teeth and recesses. A hole is provided in the brace and this hole has its sides diagonal to the rail to receive a 45 tie spike. The notches in the wedge are made to be brought into alinement with a part of the hole in the brace so that when the spike is arranged in the hole, one corner of the spike will engage a recess in the wedge.

50 The accompanying drawings illustrate a selected embodiment of the invention and the views therein are as follows:

Fig. 1 is a plan view of a section of track, including a switch point and shows the manner in which the plates and braces are applied 55 to the rails.

Fig. 2 is a detail sectional view on the line 2—2 of Fig. 1.

Fig. 3 is a detail top plan view partly in section showing the improved brace. 60

Fig. 4 is an exploded or disassembled view of the parts constituting the improved rail bracing means.

Referring to the drawings, there is shown in Fig. 1 a section of a track at a switch 65 point and includes the usual track ties 10, rails 11, and switch points 12.

The rails 11 comprise the usual head 13, the web 14, and the bottom flanges 15.

A plate 16 adapted to rest on top of a tie 10 is provided with a hole 17 to receive a spike 18 for fastening the plate to the tie. The plate is also provided with an upstanding portion 19 upon which the bottom flange 20 of the switch points slide. The upstanding portion 19 is provided with a vertical shoulder 21 against which the edge 22 of the rail flange 15 abuts, Fig. 2. A rail brace 23 is provided to hold the edge 22 against the shoulder 21 and to brace the rail on the side 75 opposite the switch points. This brace comprises a vertical portion 24 which bears against the web 14, and a base 25 which includes an inclined portion 26 and is adapted to rest on top of the plate 16 and engage a 80 rail flange 15. The upper portion of the brace is provided with a downwardly and inclined edge 27 which fits under the rail head 13, Fig. 2. An inclined reinforcing member 28 integrally connects the several 85 portions together and merges with a horizontal portion or flange 29 integrally connected with the flat portion of the base 25. This portion 29 is spaced upwardly from the top face of the plate 16, Figs. 2 and 3. A 90 pair of oppositely disposed holes 30 arranged on either side of the member 28 are provided in the brace base 25 and are adapted to aline with spike holes 31 provided in the plate 16.

95 The holes 30 are elongated laterally, Fig. 4, 100

to permit lateral movement of the brace. Spikes 32 pass through the alined holes 30 and 31 in the brace and plate respectively for securing the brace and plate rigidly to a tie 5 10.

The plate 16 is also provided with an upstanding fin or ridge 33 to engage the outer straight edge 34 of the wedge 35. The wedge 35 comprises a base 36 which is adapted to 10 lie on top of the plate 16 and has an upstanding portion 37 which has its inner edge 38 inclining rearwardly, Fig. 4. The outer edge 39 of the brace 25 inclines rearwardly and is adapted to abut against the inner inclined 15 edge 40 of the wedge. The upstanding horizontal portion 29 of the base also has an inclined outer edge 41 being parallel with the edge 39 of the base and is adapted to bear against the inclined edge 38 of the wedge 35. 20 The upstanding horizontal portion or flange 29 of the brace is provided with a spike hole 42 provided substantially in the center of the base at a point where the inclined member 28 integrally connects with the horizontal portion 29 of the base. This hole 42 is 25 adapted to come into alinement with a hole 43 in the plate 16, the hole 42 being formed at an angle relative to the holes 30.

The wedge 35 is provided with a plurality 30 of alternately spaced teeth 44 and recesses 45 to receive a spike 46 which passes through the alined holes 42 and 43, one corner of the spike being received in a recess 45 with the sides 47 of the spike engaging the inclined 35 faces 48 of the teeth. The hole 42 is arranged so that the sides 47 of the spike will register with the sides 49 of the hole, the sides being at an angle to the longitudinal center line of the rail. The hole 42 is provided at the 40 specified angle so that the outer corner 50 of the spike will be received within the recesses 45 provided in the wedge and engage the inclined faces 48 of the teeth 44.

In practice, the plate 16 is maintained on 45 top of a tie and a spike 18 passed through the hole 17 and into a tie 10 to fasten the plate in position on the tie. The rail 11 is mounted on top of the plate with the edge 21 of the flanges 15 abutting against the 50 vertical shoulder 22 on the upstanding member 19. The brace 23 is then placed into position, the base 25 resting upon the plate 16 and the inclined portion 26 and the vertical portion 24 engaging a flange and web respectively of the rail, the brace being positioned relative to the plate so that the holes 30 will aline with the holes 31 in the plate to receive the spikes 32. The spikes 32, however, are not driven home until the brace is 55 finally and rigidly fastened in place. The wedge 35 is then arranged in position between the upstanding fin 33 on the plate and the edge 39 of the brace base. The horizontally extending flange 29 will have its bottom supported on the top of the wedge base 60 65

36 with its edge 41 engaging the inclined side 38 of the upstanding wedge portion 37. The wedge is then positioned by driving the end of the wedge to move the brace tightly against the rail. When the wedge is driven 70 the required distance, a spike 46 is inserted through the alined holes 42 and 43 in the brace and plate respectively to hold the wedge, brace and plate in position. The spike 46 will be received in one of the recesses 45 and engage the sides 48 of the teeth 44. During the driving operation of the wedge it is preferable that a recess 45 be in proper position relative to the hole 42 in the brace with the sides 49 of the hole 42 alining with the edges of the recess 45. If, however, these edges do not come into perfect alinement, the driving of the spike 46 will move the wedge sufficiently one way 80 or another so that the spike can be driven home. After the wedge 35 has been positioned and the spike 46 driven tightly through the holes 42 and 43 and into the tie 10, the spikes 32 are driven home and the rail is rigidly supported by the brace with the edge 21 of the flange tightly engaging the vertical shoulder 22. 90

During constant use, the brace may become loose relative to the rail so it will be necessary to adjust the brace. This is done by 95 merely removing the spike 46, driving in the wedge until another recess toward the thick end of the wedge comes into alinement with the hole 42 and then again driving the spike in place. The elongated slots or holes 30 in 100 the brace permit the brace to be slid laterally relative to the plate with the spikes 32 engaging the holes 31 in the plate. The elongated slot or opening 43 in the plate permits 105 lateral shifting of the brace relative to the plate when the wedge is driven in position. The hole 42 in the brace and the holes 31 in the plate are substantially the same size as the spikes, thereby preventing the spikes from wobbling or shifting and still permitting the brace to be moved laterally by 110 means of the wedge.

The invention comprises a thoroughly efficient and relatively simple rail brace which is comparatively economical to manufacture. 115 The wedge is made from a single piece of material and is held in position by means of the spikes which assist in holding the brace and plate in position, and no additional members are required to prevent the wedge from 120 moving in respect to the plate and brace during normal operation. The present brace is adapted to be applied to plates already in use.

Changes may be made in the form, construction, and arrangement of the parts without departing from the spirit of the invention or sacrificing any of its advantages, and the right is hereby reserved to make all such changes as fairly fall within the scope of the following claims. 125 130 135

The invention is hereby claimed as follows:

1. In combination a rail brace, a wedge co-operating with said brace to effect adjustment thereof, and a spike engageable with the brace and wedge for holding the brace and wedge in adjusted position.

2. In combination a rail brace, a wedge co-operating with said brace to effect adjustment thereof, means for fastening said brace to a tie, said wedge being provided with recesses, said means engaging the brace and a recess for maintaining the wedge in position relative to the brace.

3. In combination a rail brace, a wedge co-operating with said brace to effect adjustment thereof, a plurality of teeth on one side of said wedge, and a spike passing through a part of said brace and engaging a pair of said teeth for maintaining the wedge in position relative to said brace.

4. In combination a rail brace, a wedge co-operating with said brace to effect adjustment thereof, said brace having an opening therein, and means passing through said opening and engaging a side of the wedge for holding said wedge in position relative to said brace.

5. In combination a rail brace, a wedge co-operating with said brace to effect adjustment thereof, said brace having an opening therein, teeth on said wedge and having recesses therebetween, one of said recesses adapted to be brought into alignment with said opening, and means passing through the opening and recess for holding the wedge in position relative to the brace.

6. In combination a rail brace, a wedge co-operating with said brace to effect adjustment thereof, said brace having an opening therein, teeth on said wedge and having recesses therebetween, any one of said recesses being adapted to be brought into registration relative to said opening upon movement of said wedge, and a spike passing through said opening and registered recess for maintaining said wedge in position relative to said brace.

7. In combination a rail brace, a wedge engageable with said brace for providing adjustment thereof relative to a rail, and a plurality of spikes for holding said brace in place, one of said spikes engageable with said wedge for maintaining said wedge in position relative to said brace.

8. In combination a rail brace, a wedge engageable with said brace for providing adjustment thereof relative to a rail, and a plurality of spikes for holding said brace in place, at least one of said spikes having complementary engagement with the wedge for holding said wedge in adjusted position.

9. In combination, a plate having upstanding shoulders, a rail engageable with one of said shoulders, a brace engageable with said rail, a wedge engageable with said brace and the other of said shoulders for providing

lateral adjustment of said brace upon movement of said wedge, a spike passing through said brace and plate and engageable with said wedge for rigidly holding all of said members in position.

10. In combination, plate having upstanding shoulders, a rail engageable with one of said shoulders, a brace engageable with said rail, a wedge engageable with said brace and the other of said shoulders for providing lateral adjustment of said brace upon movement of said wedge, said brace and plate being provided with aligned openings therein, means passing through said brace and plate for securing the rail to the plate and the plate and brace to a tie, and means passing through the openings in the brace and plate and into the tie and engaging said wedge.

11. In combination, a plate having parallel upstanding integral shoulders formed on its top and on opposite sides thereof, a rail engageable with one of said shoulders, a brace engageable with said rail, a wedge engageable with said brace and the other of said shoulders for providing lateral adjustment of said brace upon movement of said wedge, said brace and plate being provided with aligned openings therein, some of said openings being elongated to permit adjustment of the brace relative to the plate and rail, said wedge having recesses along one edge thereof, and means engageable with a recess and engaging a tie for holding the wedge in position relative to the brace and plate.

12. In combination, a plate having upstanding shoulders, a rail engageable with one of said shoulders, a brace engageable with said rail, a wedge engageable with said brace and the other of said shoulders for providing lateral adjustment of said brace upon movement of said wedge, spaced teeth on said wedge, and fastening means passing through the brace, into a space between a pair of said teeth and engaging a tie whereby said wedge is rigidly positioned relative to said brace.

13. In combination a rail brace having an inclined edge, a wedge engageable with the inclined edge, a shoulder engageable by said wedge whereby said wedge may be moved to move the brace in position relative to a rail, teeth on the wedge, and means passing through the brace and engaging a tie and cooperating with said teeth for rigidly maintaining said wedge in position relative to said brace.

14. In combination a rail brace having an inclined edge, a wedge engageable with the inclined edge, a shoulder engageable by said wedge whereby said wedge may be driven inwardly to move the brace tightly against a rail, said wedge having recesses along one edge thereof, and a single spike engaging a recess and a tie for holding the wedge in position.

15. In combination a rail brace having an

inclined edge, a wedge engageable with the inclined edge, a shoulder engageable by said wedge whereby said wedge may be driven inwardly to move the brace tightly against a rail, said wedge being provided with recesses, and a spike engageable with a recess for holding the wedge in position, said spike being so positioned that its normal vertical plane is at an angle to a line parallel with the rail.

10 16. In combination a brace adapted to support or brace a rail, a wedge having V-shaped recesses or notches and adapted to be wedgely moved relative the brace to permit adjustment of the brace relative to the rail, and fastening means having two sides thereof engaging the sides of a V-shaped recess for holding the wedge in position.

15 In witness whereof, I have hereunto sub-
20 scribed my name.
